UNITED STATES PATENT OFFICE.

CLINTON E. WOODS, OF BRIDGEPORT, CONNECTICUT, ASSIGNOR TO AMERICAN GRAPHOPHONE COMPANY, OF BRIDGEPORT, CONNECTICUT, A CORPORATION OF WEST VIRGINIA.

TALKING-MACHINE.

1,106,269.

Specification of Letters Patent.

Patented Aug. 4, 1914.

Application filed December 4, 1912. Serial No. 734,913.

To all whom it may concern:

Be it known that I, CLINTON E. Woods, a citizen of the United States, and a resident of Bridgeport, Fairfield county, Connecticut, have invented a new and useful Improvement in Talking-Machines, which invention is fully set forth in the following specification.

This invention relates to a single unitary 10 motor-plate, standardized and interchangeable, intended primarily for use with talking-machines that employ disk sound-records and particularly adapted for use with talking-machines of the class known as 15 "concealed-horn" or "cabinet" machines, although it may likewise be employed with so-called "visible-horn" machines. However, my invention is also applicable to talking-machines that employ cylindrical sound- 20 records.

For convenience, I shall explain the invention with particular reference to disk machines of the "concealed-horn" type where the sound-conveyer extends downward and discharges beneath the level of the 25 turn-table.

Heretofore, in assembling such machines and installing them in their cabinets, the motor has had to be mounted in a particular 30 position, on or beneath a shelf or other suitable support; openings must be properly plotted and made for the main motor-shaft, for the motor-controlling devices, and particularly for the sound-passage (through 35 the tone-arm into the horn), and particular pains are to be taken in order that all the various mechanical parts should be brought into proper relation to each other and to the cabinet. In each separate installation, 40 these holes must be carefully located by skilled workmen; indeed, in the various styles and sizes of machines put out by the same manufacturer, the machine devices referred to have been located in a wide variety 45 of different positions with respect to each other (and at different distances). In short, it has been a matter of considerable skill, requiring expert labor, to install the machines properly in the cabinets; and it 50 sometimes happens that the installation turns out unsatisfactory, and requires taking apart and re-installing. All of this has proved very expensive, besides causing delays in the original assembling and in the 55 test rooms. I have avoided all these diffi-

culties by producing a single unitary rigid motor-plate or talking-machine base,—a standardized product containing carefully located openings, bearings, etc., for use interchangeably with different styles of talking-machines. By means of my invention, such standardized motor-plates can be struck up from sheet steel, the motor can be mounted thereon in the factory, all the parts brought automatically into proper relation, 60 and the whole installed in the cabinet by unskilled labor.

A preferred embodiment of my invention is illustrated in the annexed drawings, in which—

Figure 1 is a plan, and Fig. 2 an edge view, of a preferred motor-plate embodying my invention, shown as equipped with a swinging tone-arm and its sound-box and stylus.

The motor-plate 1 is of sheet steel, stamped up into substantially the configuration indicated, and preferably provided with stiffening-corrugations 2.

3, 4, and 5 represent openings for securing the depending motor, as by rivets, bolts, or other suitable means.

6—6 are conveniently-located finger-holes for lifting the plate with its dependent motor into or out of the talking-machine cabinet.

7 represents the central opening, through which will protrude the upright motor-shaft for carrying the turn-table of the talking-machine.

8 is a lateral projection for presenting, at suitable distance from the center 7, the opening in which is secured the stationary member 9 for the swinging tone-arm 10. At the proper distance from the extension 8 and from the motor is a small extension 11, having an opening 12, through which extends the stop-and-start button 13 (shown in Fig. 2) for the motor. At 14 is a similar extension having an opening for the speed-regulator 15 (Fig. 2). Intermediate the projections 11 and 14 is a projection 16 having the curved slot 17, adjacent to which is the scale 18, with which co-acts the pointer 19 of the speed-indicator.

20 is a conveniently-located projection for carrying a plurality of depressed cups 21, for holding reserve supplies of various styles of reproducing-needles (e. g., "hard," "medium," "soft" and "fiber"). Pref-

erably, the metal is stamped up around the margin of each cup-opening, to produce the rims 22.

23 is still another conveniently-located 5 projection from the plate 1, in which is stamped the opening for the cup 24 for used needles; such needles being dropped in turn through a little opening 25 in a detachable cup 26 fitted into the pressed-up flange 24 10 (similar to the flanges 22).

With my new motor-plate, the motor (whether a spring motor or an electric motor) is readily secured to the bottom of the plate 1, as by means of screws passing 15 through the openings 3—5, as explained. This brings the start-and-stop mechanism in proper position for control by the button 13, which is readily put into place and connected up; this also brings the speed-controlling 20 mechanism into position where the speed-regulator 15 can be readily inserted through its opening in projection 14, and properly connected up; and likewise brings the speed-indicator 19 into proper position where it 25 can be seen beneath the slot 17. Finally, the tone-arm is properly secured over its hole in projection 8, which is so located as to bring the stylus into proper relation to the sound-record. All the mechanical parts being 30 thus assembled upon my novel motor-plate as the base, the entire structure can be readily applied to any cabinet, and secured in place as by screws passing through suitably located holes 27. This latter installing 35 can be carried out in the cabinet-making department, by unskilled labor.

It will be understood that some of the projections (with their cups or openings) may be omitted, or additional projections

with openings or cups provided; and that 40 the relative locations of the respective projections and openings, or the distance of each from the center, can be varied, according to the type and size of motor, or the particular construction intended to be employed, without in any case departing from the spirit of my invention. In short, my invention is not limited to the precise construction and arrangement of parts, but 45 may be varied considerably. 50

Having thus described my invention, I claim:

1. A sheet metal motor-board for talking machines, having an approximately circular body portion, with a centrally placed motor-shaft opening therein, and two marginal projections through one of which is a tone-arm opening, and through the other of which there is an oblong slot or opening with a speed-indicating scale adjacent 60 thereto. 65

2. A sheet metal motor-board for talking machines, having an approximately circular body portion, with a centrally placed motor-shaft opening therein, strengthening corrugations concentric with said motor-shaft opening, and marginal projections from 65 said circular body portion having openings to accommodate the tone-arm, speed-regulator and a start-and-stop element. 70

In testimony whereof I have signed this specification in the presence of two subscribing witnesses.

CLINTON E. WOODS.
